(57) **ABSTRACT**

The present invention provides a method of dispensing a plurality of treating compositions into a multistage automatic washing machine. The method comprises operating a device in the machine. The device comprises at least two chambers. Each chamber contains a treating composition. The chambers are activated in response to input from a sensor. The device has an associated reservoir for collection of wash liquor.

**CROSS-REFERENCE TO RELATED
APPLICATIONS**

This application is a divisional application of, and claims priority to, U.S. Pat. No. 9,687,139, filed on 6 May 2014 and issued on 27 Jun. 2017, which is a US National Stage of International Application No. PCT/GB2012/052892, filed 22 Nov. 2012, which claims the benefit of GB 1120117.5, filed 22 Nov. 2011, each of which is herein fully incorporated by reference.

BACKGROUND OF THE DISCLOSURE

1. Field of the Disclosure

This disclosure relates to the process of using multiple detergent compositions, rinse aids, and other additives within one complete wash cycle of an automatic washing machine.

2. Background

The various cleaning compositions may be dosed into the machine at varying quantities, times, sequences, and for varying durations during a washing machine cycle. The use of multiple cleaning compositions allows for increased and optimized cleaning performance.

Current conventional systems used in automatic dishwashers only dose one detergent composition per wash cycle with the optional addition of a rinse agent composition at the very end of the washing machine cycle. The detergent compositions are primarily either enzymatic based or incorporate a hypohalite oxidative bleach (e.g., sodium hypochlorite, sodium dichloroisocyanurate, etc.).

Enzymatic detergents provide excellent cleaning on enzyme sensitive soils (primarily protein and starch based) but fail to provide performance on hard to remove stains, such as coffee, tea, and tomato stains.

Hypohalite based (for example, chlorine bleach based) detergents provide excellent cleaning on the hard to remove stains but fail to provide performance on the enzyme sensitive soils.

Because enzymes and hypohalite oxidizing bleaches are incompatible within the same formula matrix, the consumer must make a trade-off decision on performance and use one detergent composition or the other. This presents an obvious dilemma to the consumer—whether to get good cleaning on an enzymatic sensitive stain to the detriment of a hard to remove stain or vice versa.

The use of multiple detergent compositions within one washing machine cycle would mitigate this trade-off decision and provide optimal performance across the range of stains and soils normally encountered in an automatic dishwasher. However, given the incompatibility of enzyme based detergents and hypohalite detergents, the detergent compositions must be kept separate and dosed at different times so that the performance of each detergent is not affected by the presence of the other detergent.

Thus, an object of the present disclosure is to provide a method of dispensing a plurality of treating compositions into a multistage automatic washing machine, as well as

2

devices for dispensing a plurality of treating compositions into various automatic washing machines.

BRIEF SUMMARY OF THE DISCLOSURE

5

As specified in the Background Section, there is a great need in the art to identify technologies for improving methods and devices for automatic dishwashing machines. Embodiments of the present disclosure relate generally to devices for dispensing a plurality of treating compositions into various automatic washing machines and more specifically to devices for dispensing a plurality of treating compositions into multistage automatic washing machines and to removable, automatic washing machine independent devices for dispensing a plurality of treating compositions in multistage automatic washing machines.

10

In one aspect, the present disclosure provides a removable, automatic washing machine independent device, for dispensing a plurality of treating compositions in a multistage automatic washing machine, comprising:

15

a cartridge, the cartridge including at least two chambers, each chamber containing a treating composition;

at least one sensor, wherein the chambers of the cartridge are configured to be activated in response to inputs from the at least one sensor; and

a reservoir for the collection of wash liquor in the multistage automatic washing machine,

20

wherein the at least one sensor is located such that it can monitor the wash liquor in the reservoir.

In some embodiments, the reservoir drains continuously so that the wash liquor contained within it accurately reflects the current parameters of the wash liquor inside the multistage washing machine.

25

In other embodiments, the device comprises two or more sensors.

In still other embodiments, the cartridge comprises at least two different treating compositions.

30

In some embodiments, the reservoir has an inlet and an outlet.

In some embodiments, the at least one sensor is located in the reservoir.

35

In some embodiments, the device further comprises a chamber suitable for activation in a pre-rinse segment, which comprises an enzymatic detergent treating composition.

In other embodiments, the device further comprises a chamber suitable for activation in one of a wash and rinse segment, which comprises a hypohalite/peroxygen detergent treating composition.

40

In still other embodiments, the device further comprises a chamber suitable for activation in one of a wash and rinse segment, which comprises a rinse agent treating composition.

45

In yet other embodiments, the device further comprises a chamber suitable for activation in a treatment segment, which comprises one of an anti-lime agent and a water treatment agent treating composition.

50

In some embodiments, in operation the cartridge interacts with a cartridge sensor within the automatic washing machine, the cartridge sensor sensing a parameter of the automatic washing machine wash liquor and conveying the parameter back to the cartridge, influencing the operation of a cartridge chamber.

55

In other embodiments, the cartridge sensor senses the turbidity of the automatic washing machine wash liquor.

In still other embodiments, the cartridge sensor senses the temperature of the wash liquor in the automatic washing machine.

In some embodiments, the cartridge sensor senses the presence of water within the automatic washing machine.

In some embodiments, the automatic washing machine is an automatic dishwashing machine.

In some embodiments, the reservoir comprises a baffle.

In other embodiments, the reservoir is covered by a gauze.

In some embodiments, the at least one sensor is independently selected from the group consisting of a turbidity sensor, a temperature sensor, a water sensor, a moisture sensor, a water hardness sensor, a light sensor, a conductivity sensor, a vibration sensor and a sound sensor.

In some embodiments, the reservoir fills in accordance with the following formula:

$$(V_i^{-min} - V_o^{-min})/C_{av} > H$$

where:

V_i^{-min} Volume of water lost per minute (mm³);

V_o^{-min} =Volume of water collected per minute (mm³);

C_{av} =average cross sectional area (mm²); and

H=Height from base of trough to top edge of sensor (mm).

In other embodiments, the reservoir empties in accordance with the following formula:

$$V_o^{-min}/C_{av} > H$$

In another aspect, the present disclosure provides a removable, automatic washing machine independent device, for dispensing a plurality of treating compositions in a multistage automatic washing machine, comprising:

a cartridge, the cartridge comprising at least two chambers, each chamber comprising a treating composition;

at least one sensor, wherein the chambers of the cartridge are configured to be activated in response to inputs from the at least one sensor; and

a reservoir for the collection of wash liquor in the multistage automatic washing machine, the reservoir further comprising a wash liquor inlet, a separate wash liquor outlet through which the wash liquor can drain continuously, and the at least one sensor.

In some embodiments, the at least one sensor is independently selected from the group consisting of a turbidity sensor, a temperature sensor, a water sensor, a moisture sensor, a water hardness sensor, a light sensor, a conductivity sensor, a vibration sensor and a sound sensor.

In other embodiments, the treating compositions are compositionally different.

In another aspect, the present disclosure provides a removable, automatic washing machine independent device, for dispensing a plurality of treating compositions in a multistage automatic washing machine, comprising:

a first chamber comprising a first bleach-containing treating composition;

a second separate chamber comprising a second enzyme-containing treating composition which is different to the first treating composition;

at least one reservoir for collection of wash liquor, the reservoir further comprising a water inlet and a separate draining hole as an outlet; and

one or more sensors able to monitor wash liquor in the reservoir.

In some embodiments, the reservoir drains continuously.

In other embodiments, the device comprises two or more sensors.

These and other objects, features and advantages of the present disclosure will become more apparent upon reading

the following specification in conjunction with the accompanying description, claims and drawings.

BRIEF DESCRIPTION OF THE DRAWING

5

The accompanying FIGURE, which is incorporated in and constitutes a part of this specification, illustrates several aspects described below.

10 FIG. 1 depicts a modified Bernoulli's energy balance showing that the sum of the energy at point 2 must be equal to the sum of the starting energy at point 1.

DETAILED DESCRIPTION OF THE DISCLOSURE

Definitions

As specified in the Background Section, there is a great need in the art to identify technologies for improving 20 methods and devices for automatic dishwashing machines. Embodiments of the present disclosure relate generally to devices for dispensing a plurality of treating compositions into various automatic washing machines and more specifically to devices for dispensing a plurality of treating compositions into multistage automatic washing machines and to removable, automatic washing machine independent devices for dispensing a plurality of treating compositions in multistage automatic washing machines.

To facilitate an understanding of the principles and features of the various embodiments of the disclosure, various 30 illustrative embodiments are explained below. Although exemplary embodiments of the disclosure are explained in detail, it is to be understood that other embodiments are contemplated. Accordingly, it is not intended that the disclosure is limited in its scope to the details of construction and arrangement of components set forth in the following 35 description or examples. The disclosure is capable of other embodiments and of being practiced or carried out in various ways. Also, in describing the exemplary embodiments, specific terminology will be resorted to for the sake of clarity.

40 It must also be noted that, as used in the specification and the appended claims, the singular forms "a," "an" and "the" include plural references unless the context clearly dictates otherwise. For example, reference to a component is intended also to include composition of a plurality of components. References to a composition containing "a" constituent is intended to include other constituents in addition to the one named. In other words, the terms "a," "an," and "the" do not denote a limitation of quantity, but rather denote the presence of "at least one" of the referenced item.

45 Also, in describing the exemplary embodiments, terminology will be resorted to for the sake of clarity. It is intended that each term contemplates its broadest meaning as understood by those skilled in the art and includes all technical equivalents which operate in a similar manner to accomplish a similar purpose.

50 Ranges may be expressed herein as from "about" or "approximately" or "substantially" one particular value and/or to "about" or "approximately" or "substantially" another particular value. When such a range is expressed, other exemplary embodiments include from the one particular value and/or to the other particular value. Further, the term "55 about" means within an acceptable error range for the particular value as determined by one of ordinary skill in the art, which will depend in part on how the value is measured

or determined, i.e., the limitations of the measurement system. For example, "about" can mean within an acceptable standard deviation, per the practice in the art. Alternatively, "about" can mean a range of up to $\pm 20\%$, preferably up to $\pm 10\%$, more preferably up to $\pm 5\%$, and more preferably still up to $\pm 1\%$ of a given value. Alternatively, particularly with respect to biological systems or processes, the term can mean within an order of magnitude, preferably within 2-fold, of a value. Where particular values are described in the application and claims, unless otherwise stated, the term "about" is implicit and in this context means within an acceptable error range for the particular value.

Similarly, as used herein, "substantially free" of something, or "substantially pure", and like characterizations, can include both being "at least substantially free" of something, or "at least substantially pure", and being "completely free" of something, or "completely pure".

By "comprising" or "containing" or "including" is meant that at least the named compound, element, particle, or method step is present in the composition or article or method, but does not exclude the presence of other compounds, materials, particles, method steps, even if the other such compounds, material, particles, method steps have the same function as what is named.

Throughout this description, various components may be identified having specific values or parameters, however, these items are provided as exemplary embodiments. Indeed, the exemplary embodiments do not limit the various aspects and concepts of the present disclosure as many comparable parameters, sizes, ranges, and/or values may be implemented. The terms "first," "second," and the like, "primary," "secondary," and the like, do not denote any order, quantity, or importance, but rather are used to distinguish one element from another.

It is noted that terms like "specifically," "preferably," "typically," "generally," and "often" are not utilized herein to limit the scope of the claimed disclosure or to imply that certain features are critical, essential, or even important to the structure or function of the claimed disclosure. Rather, these terms are merely intended to highlight alternative or additional features that may or may not be utilized in a particular embodiment of the present disclosure. It is also noted that terms like "substantially" and "about" are utilized herein to represent the inherent degree of uncertainty that may be attributed to any quantitative comparison, value, measurement, or other representation.

The dimensions and values disclosed herein are not to be understood as being strictly limited to the exact numerical values recited. Instead, unless otherwise specified, each such dimension is intended to mean both the recited value and a functionally equivalent range surrounding that value. For example, a dimension disclosed as "50 mm" is intended to mean "about 50 mm."

It is also to be understood that the mention of one or more method steps does not preclude the presence of additional method steps or intervening method steps between those steps expressly identified. Similarly, it is also to be understood that the mention of one or more components in a composition does not preclude the presence of additional components than those expressly identified.

The materials described hereinafter as making up the various elements of the present disclosure are intended to be illustrative and not restrictive. Many suitable materials that would perform the same or a similar function as the materials described herein are intended to be embraced within the scope of the disclosure. Such other materials not described herein can include, but are not limited to, materials that are

developed after the time of the development of the disclosure, for example. Any dimensions listed in the various drawings are for illustrative purposes only and are not intended to be limiting. Other dimensions and proportions are contemplated and intended to be included within the scope of the disclosure.

Devices and Methods of the Disclosure

An object of the present disclosure is to provide a method of dispensing a plurality of treating compositions into a multistage automatic washing machine comprising an operating device in the machine, the device comprising at least two chambers, each chamber containing a treating composition, wherein the chambers are activated in response to input from a sensor, characterized in that the device has an associated reservoir for collection of wash liquor.

A plurality of reservoirs may be present.

Another object of the present disclosure is to provide a device for dispensing a plurality of treating compositions into a multistage automatic washing machine comprising cartridge in the machine, the cartridge including at least two chambers, each chamber containing a treating composition, wherein the chambers are activated in response to input from a sensor, characterized in that the device has an associated reservoir for collection of wash liquor.

In a further object of the present disclosure there is provided a removable, automatic washing machine independent device, for dispensing a plurality of treating compositions in a multistage automatic washing machine, comprising

- 25 a) a cartridge, the cartridge including at least two chambers, each chamber containing a treating composition,
- 20 b) at least one sensor, wherein the chambers of the cartridge are activated in response to inputs from the at least one sensor,
- 30 c) a reservoir for the collection of wash liquor in the multistage automatic washing machine, and

characterised in that the sensor is located within the device such that it can monitor the wash liquor in the reservoir.

40 The device may have a cartridge with at least 7 chambers, preferably 10 chambers, more preferably at least 15 chambers and most preferably at least 18 chambers.

The device may be powered by battery.

45 The device may dispense at least two different treating compositions. For example, these may comprise a detergent and a booster agent or a detergent and a rinse aid.

Preferably the device will dispense at least three different treating compositions. Each composition may be dispensed independently based on the sensory inputs.

50 The device may have software to control the dispensing of the treating compositions based on the sensory inputs.

The device is ideally completely washing machine independent being able to be placed inside any commercially available washing machine.

55 With the use of the method and device of the disclosure, it has been found that optimal (and highly sophisticated) device operation can be achieved. This has been speculated as being because of many factors including that (in comparison to many prior art documents) the device is able to discern phases within a machine cycle wherein the amount of wash liquor/water is low/zero, e.g. such as a drying phase. These phases typically are indicative a change in the nature of a cycle of a machine and thus are a significant guiding feature. Additionally when the reservoir contains a detectable level of wash liquor the parameters of said water can be measured and the right level of the right detergent may be dosed into the wash liquor. Overall the device enables

intelligent dosing of detergent compositions (in terms of the total levels and the contents thereof) at various points of a wash cycle in response to the wash conditions being experienced.

Generally the reservoir is integrated into the device. As such, it is preferred that the reservoir is disposed adjacent to the remainder of the device.

Preferably, the sensors are disposed within the reservoir, e.g. at or near the bottom thereof. By doing this it has been found that the amount of "dead time" in which the device is unable to respond to, for example, water presence in the machine (and any attributed properties of said water) is reduced. Further, it is postulated that situating the sensors in a reservoir enables more accurate monitoring of changing parameters than could be achieved in a closed reservoir

Preferably, the sensors are in the same plane. This is useful in that each sensor is then equally exposed to the wash liquor to ensure that overall operation of the device is optimized. It is appreciated the sensors could have different sizes, thus in this regard it is meant that at least a portion of a sensing part of each sensor is preferably in or near the same plane as the remaining sensors.

Where a plurality of reservoirs are present, sensors may be housed within separate reservoirs.

Preferably, the reservoir fills in accordance with the following formula:

$$(V_i^{-min} - V_o^{-min})/C_{av} > H$$

Where:

V_o^{-min} =Volume of water lost per minute (mm^3);

V_i^{-min} =Volume of water collected per minute (mm^3);

C_{av} =average cross sectional area (mm^2); and

H =Height from base of trough to top edge of sensor (mm).

Preferably, the reservoir empties in accordance with the following formula:

$$V_o^{-min}/C_{av} > H$$

By filling/emptying in accordance with one or more of the formulae above, it has been found that optimal device operation may be achieved. It is suspected that this is at least partly due to quick filling and/or emptying times, which enable speedy recognition of washing cycle start points and/or emptying/drainage points. It is these points that are often associated with the need for a release of a detergent component and/or conversely the ceasing of release of a detergent component.

Preferably when water/wash liquor is present, the reservoir reaches a state in which it contains an amount of water/wash liquor to sense the properties of same in less than 1 minute. Preferably when water/wash liquor is absent the reservoir reaches a state in which it empties in less than 1 minute. This enables detection of the shortest draining periods in a wash cycle, which may be as short as 4 minutes, more likely shorter than 2 minutes, more likely shorter than 1 minute.

Most preferably then the filling/emptying time is less than 30 seconds to account for short draining cycles. In which case the formulae may be represented below:

$$(V_i^{-min} - V_o^{-min})/C_{av}, 2H$$

$$V_o^{-min}/C_{av} > 2H$$

The inlet (and possibly the outlet) may have a cover which aids the prevention of any soil particles, present in the wash liquor, from building up in the reservoir. Such a cover may be in the form of a net/gauze which allows wash liquor (but not suspended particles) to enter the reservoir.

The water throughput within a dishwasher may change depending on the dishwasher model and manufacturer. It is therefore necessary for the trough to be designed for the lowest throughput in order for the trough to fill within 30 seconds for all dishwasher systems.

The Bosh SGS58M02EU Logixx™ model has proved to have the lowest throughput of the different dishwashers tested. This dishwasher was therefore considered the appropriate for the experimental work to develop a design equation for the water trough.

The water trough should be designed within the specifications of the following equations in order for it to operate accurately for its desired function. The function of the water trough is for water to collect within the trough, to submerge sensors within 30 seconds. These sensors can be used for the detection of the conditions of the water within the dishwasher. Depending on the water conditions or how they change the device can follow an algorithm which decides at what stages formulation should be dispensed.

$$((5.66 \times 10^{-5} - 7.62 \times 10^{-3}a + 8.03 \times 10^{-2}a^2 - 2.16 \times 10^{-3}a^3 + 0.2a^4 - 441A - 4.40 \times 10^4H + 4.28 \times 10^2H^2 + 7.1 \times 10^{-5}r - 1.7 \times 10^{-5}D + 5.7 \times 10^4L) - (a2\sqrt{(2g^{1/2}z)})) / C_{av} > 2H$$

$$(a2\sqrt{(2g^{1/2}z)}) / C_{av} > 2H$$

Where:

A =the horizontal filling area;

a =the angle of the collecting area;

h =the height of the container;

r =the position in the dishwasher ($r=1$ at the centre, $r=0$ at the edge);

D =in which drawer it is placed ($D=0$, for the bottom drawer, $D=1$ for the top drawer);

C_{av} =average horizontal cross sectional area in mm^2 ;

H =Height from the base of the reservoir to the top of sensors;

h =the height of the fluid within the sensor reservoir;

$a2$ =the draining hole area;

p =the density of the fluid; and

g =gravity in terms of mm/min^2 .

The fundamentals of creating the equation above:
The Mass Balance

The water trough design equation above is in essence a mass balance for the water trough, such that the inflow of water minus the outflow of water should accumulate the volume of fluid, $C_{av}H$, in half a minute.

The general equation is:

$$(V_i^{-min} - V_o^{-min})/C_{av} > 2H$$

Experimentally Creating a Formula for V_i^{-min} to be Inserted Into the Mass Balance

In order to detail the general mass balance in terms of the parameters of the water trough, in a dishwasher system, a large amount of experimental work had to be conducted.

V_i^{-min} the volumetric flow into the water trough is a function of A , the angle of the collecting area, a , the horizontal area of the collecting area, h , the height of the container, r , the position within the dishwasher, D , the drawer in which it is placed and f , the filling of the dishwasher. The change in the volumetric flow due to a change in each of these parameters was determined. The data was then interpolated into a formula for the inflow of water into the device. This formula was then inserted into the mass balance.

Experimentally Creating a Formula for V_o^{-min} to be Inserted Into the Mass Balance

V_o^{-min} , the volumetric flow of water out of the water trough is a function of $a2$: the size of the draining hole, g : acceleration due to gravity and z : the final height of the fluid

after filling. Bernoulli's energy balance was therefore used to create a formula for the flow of water out of the water trough. This formula was then inserted into the mass balance

Bernoulli's energy balance can be applied to the container. As there can be no creation or destruction of energy the sum of the energy at point 2 must be equal to the sum of the starting energy at point 1. The following equation gives the flow of fluid at the height inserted rather than the mean volumetric flow for the entirety of the draining. The mean volumetric flow is therefore determined for the upper and lower height level V_o^{-min} . It may be noted that as V_o^{-min} is a square root function the mean of the two points will give a slightly lower value what it should be for a square root function. However this difference is considered minimum enough to be negligible.

FIG. 1 depicts the modified Bernoulli's energy balance showing that the sum of the energy at point 2 must be equal to the sum of the starting energy at point 1 as shown above. Once the crossed-out terms are removed, the equation is:

$$(PE1-PE2)=KE2$$

$$\rho g z V = \frac{1}{2} \rho v^2 V$$

$$v = \sqrt{2gz}$$

$$V_o^{-min} = a2\sqrt{(2g/z)}$$

$$V_o^{-min} = a2\sqrt{(2g/2z)}$$

Where:

PE=potential energy;
KE=Kinetic energy;

1=position 1;

2=position 2;

ρ =the density of the fluid;

$V_o^{-min}1$ =the volumetric flow at point 1;

$V_o^{-min}2$ =the volumetric flow at point 2;

g =gravity 9.81 m/s²;

$a2$ =the area of the draining hole;

$a3$ =the area of the volumetric fluid flow out of the container;

z =the height from point 1 to point 2; and

$\frac{1}{2}z$ =the mean height of the fluid during the filling process.

Assumptions:

1. Considering quasi-static state where the draining of the main cup volume is approximately equal to 0 on a short time period dt.
2. Considering friction to be negligible. This is the friction associated with shear force at the containers edge and turbulence.
3. Considering the correction factor for $a3$, area of the volumetric outflow of fluid to be negligible and therefore $a3$ to be approximately equal to $a2$.

It is important to note that the above equations and assumptions are not limiting to the present disclosure. They are provided as an example of how to calculate the required parameters of the collection reservoir for optimum performance. The skilled person will be able to vary the equations (or provide their own) above to derive the time for drainage that is desired.

The Assumptions and Methods Used to Create the Formulae

$$V_i^{-min} = f(A, a, h, r, D, f)$$

Where:

V_i^{-min} =The inflow of water into the water trough;

V_i^{-min} , the volumetric flow of water into the water trough is a function of A: the angle of the collecting area, a: the horizontal area of the collecting area, h: the height of the

container, r: the position within the dishwasher, D: the drawer in which it is placed and f: the filling of the dishwasher.

Each of these parameters were assumed independent of each other in the testing.

The Bosh Logixx™ SGS58MO2EU dishwasher was tested to have the lowest throughput of the dishwashers available and was therefore considered to be the most appropriate machine to perform the testing. This is because the dishwasher with the lowest throughput will have the lowest rate of accumulation of water and therefore the water trough should be designed for this dishwasher in order for the filling conditions to be appropriate for all dishwashers.

This testing was performed in the dishwasher using different size containers.

The data results were interpolated using Newton's interpolation to the forth degree. The larger derivatives were considered negligible when their values were sufficiently low.

$$V_o^{-min} = a2\sqrt{(gz)}$$

Where:

V_o^{-min} =The volumetric outflow of fluid from the water-trough

Using Bernoulli's equation V_o^{-min} , the mean draining rate of fluid from the container is a function of $a2$, the size of the draining hole, g , acceleration due to gravity and z , the final height of the fluid.

Considering quasi-static state where the draining of the main cup volume is approximately equal to 0 on a short time period dt.

Considering friction to be negligible. This is the friction associated with shear force at the containers edge and turbulence.

Considering the correction factor for $a3$, area of the volumetric outflow of fluid to be negligible and therefore $a3$ to be approximately equal to $a2$.

The greater time spent at lower z values than higher z values are considered negligible and therefore the change in height is assumed linear with time. This should be a reasonable assumption as $V_i^{-min} > V_o^{-min}$ i.e., the flow into the system is a lot greater than the flow out of the system and therefore the flow out of the system will have a lower influence on the rate of accumulation. Therefore $\frac{1}{2}z$ is used within this formula to indicate the mean height of the fluid.

All other influences such as fluid temperature and viscosity were considered negligible.

The reservoir may contain a baffle. This would serve to reduce the movement of water therein; thereby reducing the likelihood of the sensors being submerged and re-emerged due to ripples rather than due to filling/emptying phases of the wash cycle.

The dosing is preferably based upon feedback from a sensor within the device that determines a feature of the load such as the amount of soil thereon and/or a feature of the wash liquor, such as the temperature thereof. In this way a desired chamber in the device may then be activated. At the same time, one or more other chamber(s) may be "locked out", unable to dose its (their) material into the machine.

The sensor may include one or more of the following types of sensor: turbidity sensor, temperature sensor, water/moisture sensor, water hardness sensor, light sensor, conductivity sensor, vibration/sound sensor.

The device may have further sensors (for example of the kind above) which are, whilst associated with the device, distanced there from. For example the device may associate

11

with a relatively remote sensor which is disposed in another part of the machine and/or in a water inlet, water outlet.

In addition or as an alternative the sensors within the machine may be used to detect the type or quality of load or water hardness at the appropriate time. Generally, but not always, this occurs at the beginning of the cycle. Such detection preferably continues throughout the cycle.

For the purposes of the present disclosure, treating composition (or agent) may mean any suitable chemical formulation for use inside a ware washing machine.

Non-limiting examples include detergent compositions, bleach containing compositions, enzyme containing compositions, rinse aid compositions and water softening compositions.

In certain instances, it may be desirable to dose an enzymatic detergent first, then followed by a hypohalite detergent and then finally with a rinse aid. In other instances, it may be desirable to dose a hypohalite detergent first, then followed by an enzymatic detergent and then finally with a rinse aid. In further instances, it may be desirable to dose an enzymatic detergent first, then followed by a rinse aid; then followed by a hypohalite detergent and then finally with a rinse aid. In still further instances, it may be desirable to dose a hypohalite detergent first, then followed by a rinse aid; then followed by an enzymatic detergent and then finally with a rinse aid. In even still further instances, it may be desirable to first dose water treatment agents (for example, builders, water softeners, chelators, etc., and the like) and then follow with either an enzymatic detergent or hypohalite detergent, then either a hypohalite detergent or enzymatic detergent, and then a rinse aid. Even further instances may include a segment where a dose of anti-lime scale agent is dosed prior to the final rinse aid segment. In even further instances, it may be desirable to dose an additive (for example, a rinse aid) at the same time as the hypohalite detergent or enzymatic detergent. Those in the art will appreciate that there are numerous other segment combinations which can be envisioned, all of which are within the scope of the present disclosure.

Depending upon the treating agent to be dosed into the machine, the dosing of the detergent may take place prior to the final rinse segment or zone, preferably prior to the first wash segment or zone.

Most preferably, the automatic washing machine is an automatic dishwashing machine.

Optionally, a plurality of devices may be provided within the automatic dishwashing machine, wherein each device has a plurality of chambers for holding/dosing a treating composition.

Most preferably, the chambers of the device contain at least two different treating compositions. Optionally, each treating composition differs from each other treating composition.

The treating composition may comprise a single treating agent or compositions, or alternatively may comprise a plurality of treating agents or compositions.

The types of treating agents which can be placed individually into the separate chambers include enzymatic detergents, hypohalite/peroxygen detergents, water treatment agents, rinse aids, anti-lime scale removers, sanitizers, perfumes, and surface repair agents.

By operation of these chambers individually it has been found that the device enables intelligent dosing of detergent compositions (in terms of the total levels and the contents thereof) at various points of a wash cycle in response to the wash conditions being experienced; thereby enabling improved wash performance.

12

A typical dishwashing cycle consists of a pre-rinse segment, a wash segment, two more rinse segments, and finally, a dry segment. Some dish washing machines may have an additional segment such as treating segments (for example, a water treatment segment or an anti-lime scale segments). A timing device within the dishwasher is responsible for precisely controlling all of the electrical circuits and activating the components associated with each segment.

Preferably, the cartridge chamber that is activated in the 10 pre-rinse segment contains an enzymatic detergent and/or surfactants and/or builders.

Preferably, the cartridge chambers that are activated in the wash segment independently contain ingredients from the 15 following: a hypohalite/peroxygen detergent, enzymes, surfactants, builders, shine agents.

Preferably, the cartridge chamber that is activated in the 20 rinse segment contains a rinse agent.

Preferably, the cartridge chamber that is activated in the 25 treatment segment contains an anti-lime agent or a water treatment.

To clearly illustrate this concept the operation of the cartridge in accordance with the method of the present disclosure in a typical dishwashing machine may be as follows.

For use with a typical multistage dishwashing machine the cartridge comprises four chambers, one for each of the 30 cycles outlined above. Each cartridge chamber, independently of the other cartridge chambers may be filled, partially filled or empty. The filling of each cartridge may be dependent upon the nature of the dishwasher machine cycle, e.g., whether or not a particular segment is present in said cycle. Alternatively the user may exert some influence as to the needs of the items to be washed and the amount of treating composition added to each chamber.

The cartridges may also be sold commercially, wherein the treating agents have been added as necessary to each cartridge chamber.

Usually chamber one (for activation in a pre-rinse segment) contains an enzymatic detergent, chamber two (for 40 activation in a wash-segment) contains a hypohalite detergent, chamber three (for activation in a rinse segment) contains a rinse aid, and chamber four (for activation in a treatment-segment) contains a water treatment agent. Chambers one, two, three, and four are activated during the 45 machine dishwasher cycle in a sequential manner to dose their respective contents (if present) into the machine during a predetermined segment such that only one chamber is activated and the material therein is dosed into the machine during said segment no other chamber is activated and no other material is dosed into the machine until the prior stage has been completed.

Typical pre-programmed cycles found in automatic dishwashing machines and cycles include HEAVY and CHINA CRYSTAL. Within these and other automatic dishwasher 50 cycles, (which can, for example, be selected by the user) is an array of options. Examples of options include DELAY START, AIR DRY, LOW ENERGY RINSE, HIGH TEMP WASH, and CANCEL DRAIN.

Each cycle can have its own treating agent dispense 55 requirements, for example, for a HEAVY cycle, it may be preferred or necessary to first dose a pre-rinse agent then followed by an enzymatic detergent and then the hypohalite detergent (or vice versa) and then finally an anti-lime scale agent.

In another example, for a CHINA CRYSTAL cycle, it 60 may be preferred or necessary to first dose a pre-rinse agent, then an enzymatic detergent (or hypohalite detergent), then

13

the rinse agent, then a hypohalite detergent (or enzymatic detergent), and then finally again a rinse agent.

The skilled person will be readily able to make a selection of the required number and types of treating composition.

For a typical automatic dishwasher machine, once the machine is loaded with articles to be cleaned and/or treated, generally the following events occur when the door of the washing machine is closed and the user has selected a particular cycle (either pre-programmed or programmed).

(1) Latching the door activates the timer and other controls. The user selects a cycle by pressing a button and/or turning a dial on the front panel of the dishwasher.

(2) The timer opens a water-inlet valve and when the water reaches the appropriate level in the dishwasher tub, the water-inlet valve closes. The timer advances to activate a motor-driven pump, which sends water through the pump housing and into the spray arms and tower at a powerful rate, causing the spray arms to rotate and spray water over the dishes.

(3) As the water becomes soiled with food particles, the water circulates through a filtration system which eliminates food particles from the water.

(4) At the end of the rinse segment, the timer signals the machine to empty the water into the home's drain system. If a cycle requires another rinse segment, the timer activates the machine to refill, rinse and drain before going into the main wash segment.

(5) For the main wash segment, the timer signals the detergent dispenser to open and empty its contents into the water-filled tub.

(6) The hot water and detergent are pumped throughout the machine to break down and loosen soil on dishes and utensils. The timer then directs the pump to drain the tub and refill with clean, hot water for final rinse segments.

(7) Once the final rinse segments are completed, the automatic drying period begins.

As can be appreciated, at certain points within the above cycles, the treating agents discussed herein can be dosed into the washing machine to perform rinsing, cleaning, disinfecting, water treating, and other tasks for which the treating agents are designed.

For example, during segment (2), a water treatment agent could be dosed into the washing machine to address any water hardness issues. Of course this will vary depending upon the water quality of the individual user. Thereafter, a rinse agent could also be dosed.

For segment (5), an enzymatic detergent could be dosed first into the washing machine and allowed to work. Then a segment (5A) could be envisioned where there is a short rinse and then segment (5B) would then dose a hypohalite detergent. Then segment (6) would then follow.

As mentioned above, there can be a variety of different segments which can be placed in a variety of sequences to define a cycle. The various cycles can be pre-programmed by the washing machine manufacturer or could be programmed by the user. Also envisioned are sensors within the washing machine that could sense the article load and the soil load. In so doing, the amount of treating agent to be dosed could be changed to meet the load requirements.

In practice, the washing machine user will load the washing machine with articles to be cleaned. After selecting a pre-programmed cycle or selecting segments which form a cycle, the washing machine is turned on.

Water hardness sensors can be used. The water hardness sensor could be an ion selective electrode or detectors which can measure the amount of calcium and/or magnesium in the water. The sensor can be preset such that depending upon the

14

hardness of the water, an appropriate amount of water treating agent can be added. Water hardness is classified by the U.S. Department of Interior and the Water Quality Association and can range from soft water (0-17 mg/l or 5 ppm of hardness) to moderately hard water (60-120 mg/l or ppm of hardness) to hard water (120-180 mg/l or ppm of hardness) to very hard water (>180 mg/l or ppm of hardness). The amount of water treatment agent needed to be added to adjust the incoming water to an appropriate water hardness can be programmed into the sensor. Additionally, various types of water treatment agents are available and the sensor can be programmed to identify the water treatment agents in the cartridge through manufacturer's sensors identifying the agents which are placed on a cartridge.

Once the water hardness has been adjusted to an appropriate level, infrared and/or ultra violet sensors which are placed within the washing machine can do a survey of the load to determine the type and quantity of load. For example, the IR and/or UV sensors could send out signals to survey the load. Both enzyme sensitive and hard to remove stains, as discussed above, could be detected. If the majority of the stains were detected to be hard to remove stains, for example, red containing stains which could be indicative of a tomato based stain—identified above as preferably treated by the use of a hypohalite detergent. If detected, then a logic switch connected to the sensor would then send a signal to the chamber containing the hypohalite to be dispensed and thus a first wash segment could be commenced. Thereafter, once this wash segment was complete, the water in the cavity could be discharged, new water loaded, again check for water hardness, and then the enzymatic detergent could be charged into the machine and the second wash segment could commence. Once this wash segment was complete, the water in the cavity could be removed and the rinse segment(s) could commence.

Those in the art will appreciate that if the IR and/or UV sensors detected more protein type stains (for example, egg), then the first wash segment would be conducted using an amount of enzymatic detergent dosed into the cavity. The 40 second wash segment would then be conducted using the hypohalite detergent.

While several possible embodiments are disclosed above, embodiments of the present disclosure are not so limited. These exemplary embodiments are not intended to be 45 exhaustive or to unnecessarily limit the scope of the disclosure, but instead were chosen and described in order to explain the principles of the present disclosure so that others skilled in the art may practice the disclosure. Indeed, various modifications of the disclosure in addition to those described herein will become apparent to those skilled in the art from the foregoing description. Such modifications are intended to fall within the scope of the appended claims. The embodiments of the present disclosure are also not limited to the particular formulations, process steps, and materials disclosed herein as such formulations, process steps, and materials may vary somewhat.

All patents, applications, publications, test methods, literature, and other materials cited herein are hereby incorporated by reference in their entirety as if physically present in this specification.

What is claimed is:

1. A removable, automatic washing machine independent device, for dispensing a plurality of treating compositions in a multistage automatic washing machine, comprising:
65 a cartridge, the cartridge including at least two chambers, each chamber containing a treating composition; at least one sensor, and

15

a wash liquor reservoir for the collection of wash liquor created in the interior of the multistage automatic washing machine during operation of the multistage automatic washing machine,

wherein the wash liquor reservoir comprises a wash liquor inlet, a separate wash liquor outlet through which the wash liquor can drain continuously, and a wash liquor sensor disposed within the reservoir,

wherein the wash liquor reservoir is configured to collect a sample of the wash liquor in the wash liquor reservoir by allowing the sample to travel from the interior of the multistage automatic washing machine through the wash liquor inlet and into the reservoir, while allowing the collected wash liquor to drain continuously from the wash liquor reservoir through the separate wash liquor outlet and back into the interior of the multistage automatic washing machine,

wherein the chambers of the cartridge are configured to be activated in response to inputs from the at least one sensor, and

wherein the at least one sensor is located such that it can monitor the wash liquor in the reservoir.

2. The device according to claim 1, wherein the reservoir drains continuously so that the wash liquor contained within it accurately reflects the current parameters of the wash liquor inside the multistage washing machine.

3. The device according to claim 1, wherein the device comprises two or more sensors.

4. The device according to claim 1, wherein the cartridge comprises at least two different treating compositions.

5. The device according to claim 1 further comprising a chamber suitable for activation in a pre-rinse segment, which comprises an enzymatic detergent treating composition.

6. The device according to claim 1 further comprising a chamber suitable for activation in one of a wash and rinse segment, which comprises a hypohalite/peroxygen detergent treating composition.

7. The device according to claim 1 further comprising a chamber suitable for activation in one of a wash and rinse segment, which comprises a rinse agent treating composition.

8. The device according to claim 1 further comprising a chamber suitable for activation in a treatment segment, which comprises one of an anti-lime agent and a water treatment agent treating composition.

9. The device according to claim 1, wherein in operation the cartridge interacts with a cartridge sensor within the automatic washing machine, the cartridge sensor sensing a parameter of the automatic washing machine wash liquor and conveying the parameter back to the cartridge, influencing the operation of a cartridge chamber.

10. The device according to claim 9, wherein the cartridge sensor senses the turbidity of the automatic washing machine wash liquor.

11. The device according to claim 9, wherein the cartridge sensor senses the temperature of the wash liquor in the automatic washing machine.

12. The device according to claim 9, wherein the cartridge sensor senses the presence of water within the automatic washing machine.

13. The device according to claim 1, wherein the automatic washing machine is an automatic dishwashing machine.

14. The device according to claim 1, wherein the reservoir comprises a baffle.

16

15. The device according to claim 1, wherein the reservoir is covered by a gauze.

16. The device according to claim 1, wherein the at least one sensor is independently selected from the group consisting of a turbidity sensor, a temperature sensor, a water sensor, a moisture sensor, a water hardness sensor, a light sensor, a conductivity sensor, a vibration sensor and a sound sensor.

17. The device according to claim 1, wherein the reservoir fills in accordance with the following formula:

$$(V_i^{-min} - V_o^{-min})/C_{av} > 2H$$

where:

V_o^{-min} =Volume of water lost per minute (mm³);

V_i^{-min} =Volume of water collected per minute (mm³);

C_{av} =average cross sectional area (mm²); and

H=Height from base of trough to top edge of sensor (mm).

18. The device according to claim 1, wherein the reservoir empties in accordance with the following formula:

$$V_o^{-min}/C_{av} > H.$$

19. A removable, automatic washing machine independent device, for dispensing a plurality of treating compositions in a multistage automatic washing machine, comprising:

a cartridge, the cartridge comprising at least two chambers, each chamber comprising a treating composition; at least one sensor, wherein the chambers of the cartridge are configured to be activated in response to inputs from the at least one sensor; and

a wash liquor reservoir comprising:

a wash liquor inlet;

a separate wash liquor outlet through which wash liquor can drain continuously; and

the at least one sensor,

wherein the wash liquor reservoir is configured to collect the wash liquor, which has been created inside the multistage automatic dishwashing machine, in the reservoir and to subsequently allow the collected wash liquor to drain continuously through the outlet and back into the interior of the multistage automatic washing machine.

20. The device according to claim 19, wherein the at least one sensor is independently selected from the group consisting of a turbidity sensor, a temperature sensor, a water sensor, a moisture sensor, a water hardness sensor, a light sensor, a conductivity sensor, a vibration sensor and a sound sensor.

21. The device according to claim 19, wherein the treating compositions are compositionally different.

22. A removable, automatic washing machine independent device, for dispensing a plurality of treating compositions in a multistage automatic washing machine, comprising:

a first chamber comprising a first bleach-containing treating composition;

a second separate chamber comprising a second enzyme-containing treating composition which is different to the first treating composition;

at least one wash liquor reservoir for collection of wash liquor created in the interior of the multistage automatic washing machine during operation of the multistage automatic washing machine; and

one or more sensors able to monitor wash liquor in the reservoir,

wherein the wash liquor reservoir further comprises a wash liquor inlet, a separate wash liquor outlet through

which the wash liquor can drain continuously, and a wash liquor sensor disposed within the reservoir, wherein the wash liquor reservoir is configured to collect a sample of the wash liquor in the wash liquor reservoir by allowing the sample to travel from the interior of the multistage automatic washing machine through the wash liquor inlet and into the reservoir, while allowing the collected wash liquor to drain continuously from the wash liquor reservoir through the separate wash liquor outlet and back into the interior of the multistage automatic washing machine. 5

23. The device according to claim 22, wherein the device comprises two or more sensors. 10
